ATTORNEY.

UNITED STATES PATENT OFFICE.

JULIUS BROMBACHER, OF VERDUGO CITY, CALIFORNIA.

WATER HEATER.

Application filed July 16, 1925. Serial No. 44,089.

My invention relates to a water heater of the storage type employing automatic mechanism for regulating the heat of the water, and it has particular reference to a unit assembly of a water heating element and an automatic gas control in connection with water heater.

The prime object of the invention is to provide a heater for automatically controlling the heating and storing the heated fluid in which the mechanism for controlling the heat and the heating element constitute a self contained unit which may be quickly attached to and detached from a tank.

Storage heaters as now constructed comprise heating means and thermostatic controls interlocked in integral relation, whereby correction of any injury or damage to the heater must necessarily be attended by a complete dismantling of the units thereof at the hands of an expert and at the expense of further damage to the heater because of rusted pipes, pipe fittings and other appurtenances, the removal of which can be effected only with difficulty, and with special tools. Ordinarily it is almost impossible to remove either unions or direct joint of ordinary storage tank heater on account of size, inaccessibility and rust.

This invention is directed to the elimination of this drawback and has for it further objects to provide a heater in which the heating means, and the automatic control for such heating means are a compact unit, which may be quickly connected to and separated from, a storage tank, without any special tools, without removing the heater, and without special skill; in which the unit may be tested out independent of the storage tank; in which one unit of heating means and regulator may be readily substituted by another; in which gaskets, packing or washers may be wholly dispensed with, and in which but one element is needed to attach the unit to and detach same from the storage tank.

A preferred form of the invention is illustrated in the accompanying drawing, the figure in which is a fragmentary sectional view.

The tank for storage of water is shown at 1, and the parts appurtenant to an automatic water heater comprise the parts shown; to wit, heating cell 2, a thermostatic unit 3, a gas or other heating fluid-controlling valve 4, a burner 5, and a water circulating pipe 6,

The heating cell or element 2, is disposed above the burner 5, and comprises a hollow body of any desirable shape, having a passageway 7 extending vertically through said body, the passageway provided preferably by a tubular member 8, penetrating the cell and welded or otherwise secured to the top plate 2' and bottom plate 2'' and sealing the hollow cell 2.

A water circulating pipe 6 communicates with the interior of the cell 2 and conveys the water, passing through the pipe 3' containing the thermostatic unit 3, into the cell 2 through said pipe 6. To the top of the cell 2 is threaded or otherwise secured a pipe section 10, having a threaded end 11 arranged for engagement with supporting member 12, to which is also arranged to be fastened by threaded engagement the aforementioned pipe 3' in which is disposed the thermostatic unit 3. This pipe 3' passes through the passageway provided by the tubular member 8.

The bottom of the tank 1, is provided with a reinforcing plate 13, centrally of which is threaded or otherwise engaged therewith one end of a stud 14, which extends through a smooth bore 12' in the supporting member 12, and the other end of which stud 14 is arranged to be engaged by a nut 15, which extends through the passageway 8 in said cell and is operable against the underside of the supporting member 12, for the purpose appearing presently.

Between the supporting member 12 and plate 13 and upon seats 12^a and 13^a respectively provided in said supporting member 12 and plate 13 are placed compression rings 16 and 17, having a double taper, for the purpose of forming a perfect joint between the plates 12 and 13 which are held conjoined by the nut 15. The seats 12^a and 13^a in said supporting member 12 and plate 13, respectively, are inwardly extended and tapered and co-operate with the tapered compression rings 16 and 17 in sealing the connection of the supporting member 12, and its appurtenant parts with the plate 13 in the bottom of the tank 1.

As seen in the figure, the pipe section 10 affords direct communication between the heating cell 2 and the tank 1, which receives the heated water from the cell 2.

The assembly of the heating unit with its complementary parts, preparatory to associating it with the tank 1 of a heater, is made

by threading the upstanding pipe section 10 attached to the cell 2, into the supporting member 12, then inserting the thermostatic rod-containing pipe 3' through the tubular member 8 and threading said pipe into the member 12. The thermostatic rod 3 is passed through the compression ring 17 and into the tank 1, simultaneously with the placement of pipe 3'. The pipe 6 is then connected to the water heating cell 2, by union 6' or other means. Both the pipes 3' and 6 are connected to a fitting 19 of ordinary type for circulation of water.

The heating unit assembled, as described and comprising the parts referred to, including the gas supply valve 4, is then associated with the tank 1 in manner following. The compression rings 16 and 17 are set in position with the bottom taper in the seats 12^a of the member 12. The nut 15 is then operated on the stud 14 and thereby the supporting member 12 is moved relatively to the stationary plate 13 in the bottom of the tank 1. By this movement, the compression rings 16 and 17 are forced into their respective seats 12^a and 13^a in the plate 13 and thereby a tight and positive joint effected. The gas connection is then made at 20 and the heater is ready for use.

To disconnect the heating cell 2, and its connected parts, from the tank 1, it is only necessary to uncouple the gas connection 20 and then to remove the nut 15 from the stud 14. It will be seen, therefore, that the supporting plate or member 12 carries the entire heating, and heat-control unit and that by a single nut 15, the entire unit may be attached to and detached from a tank without special tools, without skill, and without undue cost and expense of time and labor.

What I claim is:

1. In a water heater, including a water heating means, a thermostatic regulator and appurtenances, and a tank, a plate in the bottom of said tank having extended therefrom a stud and provided with water circulating passages, a supporting member for said heating means, thermostatic regulator and appurtenances, having openings in line with the passages in said plate, means between said plate and member to connect the passages therein, and means engaging said stud to connect said member to said plate.

2. In a water heater, including a water heating cell, a thermostatic regulator and appurtenances, and a tank, a plate on the bottom of said tank having water circulating openings, a supporting member for said cell, thermostatic regulator and appurtenances having openings, compression rings between and connecting the openings in said plate and supporting member, and means to connect said member to said plate.

3. In a water heater, including a water

heating cell, a thermostatic regulator and appurtenances, and a tank, a supporting member for said cell, thermostatic regulator and appurtenances, a stud extending beyond said tank, and a nut on said stud and operable relative to said supporting member to connect said member, and the parts carried thereby, operatively to said tank.

4. In a water heater, a tank, a supporting member to which is connected a water heating cell, a thermostatic regulator and appurtenances, and a means for operatively connecting said supporting member to a tank, comprising a stud carried by said tank, and a nut on said stud and movable relative to said tank and supporting member.

5. In a water heater, including a water heating cell, a thermostatic regulator and appurtenances and a tank, a plate on the bottom of said tank having water circulating openings therein, a member carrying said cell, thermostatic regulator and appurtenances, and having openings therein registering with the openings in said plate, compression rings between said plate and member to seal the connection of the supporting member with the plate, and means for connecting said supporting member to said plate, comprising a stud extending from said plate, and a nut operable on said stud and relatively to said support.

6. In a water heater, including a water heating means, a thermostatic regulator and appurtenances, and a tank, a plate on the bottom of said tank, having water circulating openings therein, a support for said heating means, thermostatic regulator and appurtenances having openings therein registering with the openings in said plate, a water seal between said plate and support, and means for moving said support into operative connection with said plate, and pressing the water seal in the respective openings in said plate and support.

7. In a water heater, including a means for heating the water, a thermostatic regulator and a tank, a plate on the bottom of said tank having water circulating openings and a stud extending downwardly therefrom, a supporting member for said heating means, and thermostatic regulator having openings in register with the openings in said plate, means to connect said openings, said stud passing through said supporting member, and means engaging and movable on said stud to connect said member to said plate.

8. In a water heater, a tank having water circulating openings therein, a water heating unit including a thermostatic regulator and appurtenances, a member to which said water heating unit thermostatic regulator and appurtenances are connected, said member having water circulating openings therein, and means to move said member relative

to said tank to bring the respective openings in said tank and member in register and establish communication between said tank and water heating unit and thermostatic regulator.

9. In a water heating device, a tank having water circulating openings therein, a water heating unit including a thermostatic regulator and appurtenances, a member to which said water heating unit and appurte-

nances are connected, said member having water circulating openings therein in register with the openings in said tank, compressive means in and connecting the openings in said tank and member, and means to move 15 said member into operative connection with said tank and said compressive means.

In testimony whereof I have set my hand.

JULIUS BROMBACHER.
